CLAIM

The ornamental design for a ring chair as shown and described.

DESCRIPTION

FIG. 1 is a perspective view of a ring chair of the present invention;

FIG. 2 is a front plan view thereof;

FIG. 3 is back plan view thereof;

FIG. 4 is a right side elevational view thereof;

FIG. 5 is a left side elevational view thereof;

FIG. 6 is a top plan view thereof; and,

FIG. 7 is a bottom plan view thereof.

The uneven length, broken lines shown in the drawing represent surface contour shading.
